UNITED STATES PATENT OFFICE.

MAX SCHULZ, OF OLDENBURG, GERMANY.

TEMPERATURE-CONTROLLER.

1,078,752.

Specification of Letters Patent. Patented Nov. 18, 1913.

Application filed May 23, 1912. Serial No. 699,255.

To all whom it may concern:

Be it known that I, MAX SCHULZ, of Oldenburg, Germany, a subject of the King of Prussia, and whose post-office address is 7 5 Osterstrasse, Oldenburg, Grand Duchy of Oldenburg, German Empire, have invented new and useful Improvements in or Relating to Temperature-Controllers, of which the following is a specification.

10 Valves for controlling the flow of steam to heating apparatus by thermostatic action are in common use, but, where both exhaust and live steam are used conjointly in the same heating apparatus it is desirable to operate the valves controlling the separate sources of supply from one thermostat and to so coördinate the action of the two valves that all initial governing action shall take effect on the live steam valve, and any reduction of the exhaust steam consumption shall be deferred until after the live steam has been entirely shut off. Under these conditions the expenditure of live steam will be conserved to the greatest possible extent, 25 and its supply drawn upon only when the demands of the apparatus exceed the capacity of the exhaust steam supply. I have invented a simple apparatus for accomplishing this result.

30 The best form of apparatus embodying my invention at present known to me is illustrated in the accompanying sheet of drawings in which—

Figure 1 is a vertical central section of the 35 valve apparatus, and Fig. 2 is a side elevation of the same showing also certain of the connections therefor.

Throughout the drawings like reference characters indicate like parts.

40 *a* represents a valve for controlling the exhaust steam supply and *b* is a similar valve of smaller size for controlling the live steam supply. The supply pipes (not shown) are to be coupled to the upper portions of the 45 valve casings, and the outlet connections *m* and *n* are connected together as shown in Fig. 2.

e, the spindle of the exhaust steam valve is bored out, so that the rod *f* may extend 50 through it. *h*, the spindle of the live steam valve *b*, is in line with the rod *f* and spindle *e*, and has a spring head or telescoping section composed of the cylindrical case *g* containing spiral spring *s*, and head *o* of rod *f*.

This head *o* is retained in cylinder *g* by 55 lugs *p*—*p* or equivalent device.

r is a short sleeve in which the end of spindle *e* is guided. Valve spindle *h* and rod *f* are normally spaced apart by the spring *s*, in the position shown in Fig. 1, and the parts 60 are so proportioned that when both valves are wide open the right hand end of rod *f* projects beyond the end of the hollow spindle *e* of valve *a* a distance equal to the travel necessary to close valve *b*. While the 65 valves are of the partially balanced type, it is evident that there will always be a small unbalanced pressure tending to open them due to the diameters of the right hand valve ports being greater than those of the left 70 hand ports. Both valves being thus normally held wide open by the steam pressure, both exhaust and live steam will flow through them till the pressure or heat of steam in the radiating system (not shown) 75 is sufficient to operate any convenient expansion or thermostatic device (also not shown) to move the plunger *d* in valve casing extension *c*, toward the left. This plunger *d* being in line with and adapted to abut 80 against rod *f*, forces said rod to the left whenever said plunger is moved by thermostatic or other action toward the left. This motion of rod *f* is transmitted through its head *o*, the spring *s*, cylinder *g*, and valve 85 stem *h*, to valve *b* and begins to close the same, thus cutting down the live steam supply. If this does not check the rising temperature sufficiently, the live steam valve is finally closed by continued movement of *d* 90 and then further movement of rod *f* merely compresses spring *s*, and telescopes the connection to valve *b*, but the parts are so proportioned that when valve *b* is closed, the thermostatic member *d* has moved far 95 enough to strike the end of the hollow stem *e* of the exhaust steam valve *a* and so has taken up all the slack in the lost motion connection between *d* and *e*. Further action of the thermostat will then gradually close 100 valve *a*. Motion of *d* in the opposite direction reverses the above described series of steps, first opening valve *a* to its fullest extent, and then gradually opening valve *b*, to the required extent. A complete and automatic heat regulation is thus obtained, primarily through control of the live steam, 105 secondarily through controlling the exhaust

steam, by one and the same thermostatic apparatus, thereby securing the highest degree of economy in live steam consumption, evenness of regulation and simplicity of construction.

5 I have not shown and described the thermostatic apparatus as its construction forms no part of my invention, and any suitable standard type of thermostat or expansion device may be used.

10 Having described my invention, I claim:

1. In an apparatus for automatically and consecutively controlling two valves from one thermostat or equivalent device, the combination with the two valves and a thermostatically operated member, of a spring connection from said member to one valve, and a lost motion connection from said member to the other valve.

20 2. In an apparatus for automatically and consecutively controlling two valves from one thermostat or equivalent device, the combination with the two valves and a thermostatically operated member, of a spring connection from said member to one valve, and a lost motion connection from said member to the other valve, the slack of the lost motion connection being equal to the travel of the valve having the spring connection.

30 3. In an apparatus for automatically and consecutively controlling first the supply of live steam and afterward the supply of exhaust steam to a steam heating apparatus, the combination of a live steam valve and an exhaust steam valve having a common

axis for their valve spindles, the spindle of 46 the exhaust steam valve being hollow and that of the live steam valve passing through it, the live steam valve spindle having a spring controlled telescoping section, and, when both valves are fully open, projecting 45 beyond the end of the other spindle a distance equal to the full travel of the live steam valve.

4. In an apparatus for automatically and consecutively controlling first the supply of 50 live steam and afterward the supply of exhaust steam to a steam heating apparatus, the combination of a live steam valve and an exhaust steam valve having a common axis for their valve spindles, the 55 spindle of the exhaust steam valve being hollow and that of the live steam valve passing through it, the live steam valve spindle having a spring controlled telescoping section, and, when both valves are fully open, 60 projecting beyond the end of the other spindle a distance equal to the full travel of the live steam valve, together with a thermostatically controlled member movable in line with the common axis of the two valve 65 spindles; and adapted to engage their outer ends.

In testimony whereof I have hereunto set my hand in presence of two subscribing witnesses.

MAX SCHULZ.
